ANTENNA ELEMENT

Charles C. Y. Liu, Ellenville, N.Y., assignor to Channel
Master Corporation, Ellenville, N.Y., a corporation of
New York

Filed May 10, 1963, Ser. No. 74,837

Term of patent 14 years

(Cl. D26—14)

FIGURE 1 is a front elevational view of an antenna element showing my new design; and

FIGURE 2 is a fragmentary top plan view thereof to an enlarged scale with respect to FIGURE 1.

The broken line showing of an antenna crossbar in FIGURE 1 is for illustrative purposes only.

I claim:

The ornamental design for an antenna element, as shown and described.
